UNITED STATES PATENT OFFICE.

GEORGE C. ABBE AND ROY C. WILLIAMSON, OF KENNETT SQUARE, PENNSYLVANIA,
ASSIGNORS TO AMERICAN ROAD MACHINERY COMPANY, INC., OF KENNETT
SQUARE, PENNSYLVANIA, A CORPORATION OF DELAWARE.

ROAD ROLLER AND SCARIFIER.

Application filed September 24, 1924. Serial No. 739,489.

Our invention relates to an improvement in road rollers and scarifiers and is more particularly directed to the production of a convenient and economical device which may 5 be used in connection with road building and improvement operations and which will be adaptable for use in connection with road maintenance.

Heretofore there have been produced various types of road rollers powered with internal combustion engines, but such are relatively expensive in first cost and also in operation. Further, such rollers are cumbersome and primarily usable only on relatively large 15 operations.

Now it is the object of our invention to provide means whereby the well known Fordson tractor may be adapted to the production of a road roller which will be highly 20 efficient, economical and of a wide range of utility, and further to provide means whereby scarifying means may be applied to the roller with efficiency.

As a result of our invention there is provided a road rolling and scarifying device 25 essentially including a Fordson tractor which results in a device of such simplicity as to be operable by relatively unskilled hands and one for which repair parts and service are obtainable almost any where throughout the 30 country.

Having now indicated in a general way the nature, purpose and advantage of our invention, we will proceed to a detailed description thereof with reference to the accompanying drawings in which we have illustrated a preferred embodiment and in which:

Figure 1 is a side elevation of a road roller 40 embodying our invention with the scarifier elements omitted.

Figure 1^A is a sectional view on line 1^A, Figure 1.

Figure 2 is a plan view, partly in section 45 of the roller shown in Figure 1.

Figure 2^A is a perspective view of means for securing the roller wheels to their axle.

Figure 3 is a side elevation partly in section 50 of means for supporting the frame of the roller.

Figure 4 is an end view, partly in section of the subject of Figure 3.

Figure 5 is a plan view showing scarifying

device connected to the frame of the road roller. 55

Figure 6 is a partial longitudinal section of the roller showing the application and means for manipulating the scarifying device.

a represents a Fordson tractor of well known construction, from which the front axle assembly and rear wheels have been removed.

b represents a frame, bent upwardly and forwardly at its forward end as clearly 65 shown in Figure 1. The frame *b* is composed of a pair of side members, extending toward each other throughout a major portion of their length and braced by means of cross members *c* and *d* intermediate their 70 ends and by a plate *e* adjacent the forward end.

The Fordson tractor unit *a* is mounted on and supported by the frame, the forward end being supported by engagement of the 75 cross member *c* with the forward end of the crank case of the unit, in place of the front axle assembly as shown in Figure 1^A.

The rear end of the tractor unit is supported by means of brackets *e'* secured to the 80 side members of the frame. The brackets *e'*, one of which is shown in detail in Figures 3 and 4, are secured oppositely to the side members of the frame by means of rivets or bolts and are provided with a clamping 85 member *f* adapted to embrace the rear axle housing *g* of the Fordson tractor adjacent its opposite ends and secure it to the bracket by which it is supported from the frame.

Thus it will be observed that the tractor 90 unit is supported by the frame *b*, at its forward end by cross member *c* and at its rear end through being clamped to brackets *e'* secured to the side members of the frame.

Beneath the forward end of the frame *b* 95 is a wide single wheel or roller *i*, preferably made in two sections as shown. The roller *i* is mounted on an axle *j* carried by an inverted U shaped frame *k*, secured to a hanger *l* pivotally mounted beneath the forward end of the frame *b*. Secured to the frame *k* is a vertical shaft *m* upon the upper end 100 of which is secured a segmental gear *n*, adapted to be rotated, for turning the roller *i* and steering the machine, by means of 105 a suitably mounted worm gear operable by

a hand wheel *o* at the operator's station through a shaft *p* leading to the rear of the machine.

The machine is driven by a pair of wide tread wheel or roller members *q* which with the rollers *i* act to roll a surface of substantial width. The rollers *q* are mounted on an axle *r* mounted in bearings *s* formed in brackets *e'*. The drive from rear axle 10 *t* of the Fordson tractor unit is effected by means of sprockets *u* secured to the ends of the Fordson tractor axle, in place of the usual wheels, through chains *v*, to sprockets *w* on the hubs *x* of rollers *q* and which may 15 be of a size to give any desired gear reduction.

It will now be observed that the rollers *q* are driven from the rear axle of the Fordson tractor and if the rollers or wheels *q* are 20 mounted so as to turn on the axle *r*, as shown in Figure 1 the rollers *q* will have the benefit of the differential included in the Fordson tractor drive. However under certain circumstances the differential may be 25 distinctly disadvantageous as when one of the rollers *q* is running on soft or slippery surface. In order to enable the elimination of the action of the "Ford" differential on the rollers *q* under such circumstances, the 30 ends of the hubs *x* are slotted as at *y* and there are provided wheel retainers *z* adapted to slip over and be secured to the axle by means of bolts to retain the rollers thereon. The retainers are plain on one side and are 35 provided on the other side with ridges or keys *h*. If the effect of the differential be desired, the retainers are put on the axles with their plane sides against the ends of the hubs and secured to the axle, in this position the rollers may turn relatively to the 40 retainers and to the axle *r*. If, on the other hand, the effect of the differential is to be eliminated, the retainers are reversed and the keys *h* entered in the slots *y* in the hubs, 45 so that when the retainers are secured to the axle the rollers will be locked thereto and both rollers will act as a unit.

In order to provide for convenience in cranking the engine of the Fordson tractor 50 there is applied to the end of the lateral power take-off shaft a starting crank 4 accessible to the operator when at the operator's station. The end of the power take-off shaft is covered by means of a housing 55, secured to the engine crank case and extended beyond the end of the power take-off shaft for supporting the starting crank, as shown in Figure 2.

As we have indicated, our invention includes the application of a scarifying device to the roller structure, the scarifier and its application is shown in Figures 5 and 6.

Extending between the side members of frame *b* are a pair of shafts 6 and 7 supported by brackets 8 and 9 respectively se-

cured to the frame members. At intervals on shaft 6 are rotatably mounted arms 10 separated by spacers 11 to which are secured levers 12 at the free ends of which are provided clamps 13 in which are adjustably secured scarifying tools 14. At intervals on shaft 7 are secured cranks 15 which are pivotally connected to links 16, which in turn are pivotally secured to levers 12. Secured adjacently to one end of shaft 7 is a segmental gear 17 adapted to be turned by a worm 18, on the end of a vertical shaft 19 mounted in a bracket 20 and provided on its upper end with a hand wheel 21.

It will now be clear that the scarifying device is positioned beneath and supported by the frame *b* and operates between the rollers or wheels *q*. The scarifying tools 14 may be adjusted in their clamps 13 and through rotation of shaft 7 by means of hand wheel 21, which results in raising or lowering the levers 12 which, as has been described, are pivotally supported by shaft *b* through arms 10.

The operation of the device embodying our invention will, it is believed, be obvious, but it will be noted that without any change in the Fordson tractor unit, beyond the removal of the front axle assembly and rear wheels, there is provided an efficient and economical road rolling and scarifying unit to which motive means adapted for other purposes can readily be connected.

It will be understood that while in the description of the preferred embodiment of our invention we have referred to the Fordson tractor, any suitable form of tractor unit may be utilized, or, if desirable, a power unit may be built up, without departing from our invention.

Having now fully described our invention, what we claim and desire to protect by Letters Patent is:

1. A road machine comprising, in combination, a frame, a roller mounted beneath the forward end of the frame, a pair of rollers mounted oppositely at the rear of the frame, a tractor unit having a rear axle and housing therefor, means to support the unit from the frame, said supporting means including a support for the front of the tractor unit and supports for the two ends of the axle housing and means affording driving connections between the rear axle of the tractor unit and each of said pair of rollers.

2. A road roller comprising, in combination, a frame, a roller pivotally mounted beneath the forward end of the frame, brackets oppositely secured to said frame adjacent the rear end thereof, a tractor unit having a rear axle and housing therefor, means to support the forward end of the tractor unit from the frame, means to secure the rear axle housing of the unit to said brackets, an axle supported by said brack-

ets, a roller mounted on each end of said axle and means affording driving connections between the rear axle of the tractor unit and said rollers.

- 5 3. A road machine comprising a pair of rear rollers mounted on the ends of an axle, a driving sprocket connected to each roller, a frame formed of a pair of side members, and a plurality of cross members, bearings 10 for said axle connected to the side members of the frame, said side members extending upwardly at their forward ends, a third roller pivotally mounted below the forward ends of the side members of the frame, a 15 support on the frame for the front end of a tractor unit, and a clamp at each side of the frame at the rear thereof for the reception of the rear axle housing of a tractor unit.
- 20 4. A road roller comprising, in combination, a frame, a roller pivotally mounted beneath the forward end of the frame, brackets oppositely secured to said frame adjacent the rear end thereof, a Fordson tractor unit 25 having a rear axle and housing therefor, means to support the forward end of the tractor unit from the frame, clamps carried by said brackets adapted to engage the rear axle housing of said tractor unit and secure it to the frame, bearings formed in said brackets, an axle rotatably mounted in said bearings, rollers mounted on the ends of said axle, sprockets mounted on the ends of the tractor unit rear axle, sprockets secured to 30 the rollers and chains passing over said sprockets.

5. A road roller comprising, in combination, a frame, the front end of which is bent upwardly and forwardly, a roller pivotally mounted beneath the front end of the frame, a pair of brackets secured to opposite sides of the frame adjacent the rear end thereof, a Fordson tractor unit having a rear axle and housing therefor, means extending 45 transversely of the frame forming a support for the forward end of the tractor unit, means carried by the said brackets adapted

to engage the rear axle housing of the tractor, an axle supported by said brackets, rollers mounted on said axle and means affording driving connections between the rear axle of said tractor unit and said rollers.

6. A road roller having a frame comprising longitudinally extending side members, a plurality of cross members connecting the side members to each other, a roller for supporting the front end of the frame arranged to swing about a vertical axis, bearings mounted on the rear ends of the side members and extending upwardly therefrom, an axle mounted in the bearings above the side members, a roller mounted each end of the axle on the outside of the side frame members, and means on the frame for supporting a tractor unit on the frame in driving relation to the rear rollers.

7. A road roller having a frame comprising longitudinally extending side members, a plurality of cross members connecting the side members to each other, a roller for supporting the front end of the frame arranged to swing about a vertical axis, bearings mounted on the rear ends of the side members and extending upwardly therefrom, an axle mounted in the bearings above the side members, a roller mounted each end of the axle on the outside of the side frame members, means on the frame for supporting a tractor unit on the frame in driving relation to the rear rollers a pair of transverse shafts supported by the side members of the frame between the rollers on the axle, levers having road surface working means on their free ends mounted on one of said shafts, and elevating means connected to said levers and the other shaft.

In testimony of which invention, we have hereunto set our hands, at Kennett Square, Pennsylvania, on this 17th day of September, 1924.
